US00D990643S

(12) **United States Design Patent** (10) **Patent No.:** **US D990,643 S**
(45) **Date of Patent:** **** Jun. 27, 2023**

(54) **AIR CONDITIONER INDOOR UNIT**

(71) Applicant: **BEIJING XIAOMI MOBILE SOFTWARE CO., LTD.**, Beijing (CN)

(72) Inventor: **Luxi Wang**, Beijing (CN)

(73) Assignee: **BEIJING XIAOMI MOBILE SOFTWARE CO., LTD.**, Beijing (CN)

(**) Term: **15 Years**

(21) Appl. No.: **29/761,543**

(22) Filed: **Dec. 9, 2020**

(30) **Foreign Application Priority Data**

Jun. 10, 2020 (CN) 202030292640.0

(51) **LOC (14) Cl.** **23-04**

(52) **U.S. Cl.**

USPC **D23/351**

(58) **Field of Classification Search**

USPC D23/315, 333, 357, 351, 314, 325, 361, D23/385

(57) **CLAIM**

The ornamental design for an air conditioner indoor unit, as shown and described.

DESCRIPTION

FIG. 1 is a front view of a first embodiment of an air conditioner indoor unit showing the new design;

FIG. 2 is a left side view thereof;

FIG. 3 is a right side view thereof;

FIG. 4 is a top view thereof;

FIG. 5 is a bottom view thereof;

FIG. 6 is a bottom perspective view thereof;

FIG. 7 is a top perspective view thereof;

FIG. 8 is a front view of a second embodiment of an air conditioner indoor unit showing the new design;

FIG. 9 is a left side view thereof;

FIG. 10 is a right side view thereof;

FIG. 11 is a top view thereof;

FIG. 12 is a bottom view thereof; and,

FIG. 13 is a bottom perspective view thereof.

1 Claim, 7 Drawing Sheets
